Specification for Design.

Patented Jan. 14, 1919.

Application filed October 15, 1918. Serial No. 258,296. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Manufactured Pediment Figure for Furniture, Cabinet, Casket, Interior or Exterior Decoration, of which the following is a specification, reference being had to the accompanying drawing, forming a part hereof.

The drawing is an elevation or face view

of this design for manufactured pediment figure.

I claim:

The ornamental design for a manufactured pediment figure for furniture, cabinet, casket, interior or exterior decoration, substantially as shown.

In testimony whereof, I have hereunto signed my name, at Syracuse, in the county of Onondaga, and State of New York, this 26th day of Sept., 1918.

ADOLPH M. HOLSTEIN.
